PLUG FUSE

Joseph G. Biesman, Milton, Mass., assignor to
Royal Electric Company, Incorporated, Avon,
Mass., a corporation of Massachusetts

Application September 22, 1932, Serial No. 634,266

3 Claims. (Cl. 200—130)

This invention relates to electric fuses of the plug type and more particularly to a fuse provided with a glass or similar transparent top such as is shown in the Baenziger Reissue Patent No. 17,341 granted June 25, 1929. One of the objects of this invention is to increase the visibility of the fuse element so that a blown fuse is more readily detected.

Further objects are to decrease the amount of fuse material consumed in the blowing of the fuse to thereby decrease the amount of hot gas formed and the pressure within the fuse body, and to provide a body of air at atmospheric temperature with which the hot gases are immediately diluted thus to reduce the temperature of any gases which may vent from within the plug and to cause such gases as do vent to be relatively cool so that safety from fire hazard is assured even under the most adverse conditions.

For a more complete understanding of this invention, reference may be had to the accompanying drawing in which

Figure 1 is a central cross section through a plug fuse embodying this invention.

Figure 2 is a top plan of the same.

Figure 3 is a section on line 3—3 of Figure 1.

Figures 4 and 5 are perspectives of certain parts of the device.

Referring to the drawing, at 1 is shown a base of insulating material having a terminal 2 extending therethrough, this terminal being positioned to engage the usual central terminal of a threaded socket to receive the plug fuse. This base is shown as provided above its lower end with an outwardly extending flange 3 on which engages the end portion of a tubular wall 4 of a body portion 5 of the fuse which as shown is of transparent insulating material such as glass and which is provided with a window at 6 opposite to the terminal 2. The body portion and the base are shown as held together by a threaded conductive sleeve 7 which may be screwed into the threaded receiving socket. This sleeve is preferably made of sheet material with the threads rolled therein and engages a suitably threaded outer face of the wall 4 and is provided with an in-turned flange 8 at its lower end which engages beneath the flange 3 and thus retains the body and base assembled. A fuse element 10 is secured at one end to the terminal 2 as by being embedded in a plug 11 of solder or the like flowed into the hollow upper end of the terminal 2 and this fuse element is brought upwardly toward the window 6 at one side of the wall 4 and is then brought across the tubular wall

member substantially diametrically as shown at 12, is then turned backwardly and downwardly and passes out between the lower end of the wall 4 and the flange 3, and is then turned upwardly and united to the shell 7 as by solder at 14.

In order that the hot gases from the fuse when blown may be prevented from impinging directly against the wall 4 remote from the top of the body portion, a protecting sleeve of insulating material such as paper or the like, as at 15, is positioned inwardly of and substantially against the wall 4 and between it and the fuse element 10. This sleeve is shown as resting against the top face of the base flange 3 and outwardly of a flange 20 upstanding from the base 1.

Substantially midway of the portion 12 of the fuse element it is formed of reduced cross section as at 21 to localize the blowing of the fuse where it can be readily seen through the window 6, and just back of this portion this fuse element is underlaid by a relatively flimsy sheet material disk 25 of paper or the like which acts as a partition normally dividing the space enclosed by the body and base into two non-communicative compartments or chambers 26 and 27. The portion 21 of the fuse is positioned within the smaller of these chambers 26 immediately back of the window 6. This disk or partition member is so supported that when the fuse is blown it may readily be dislodged from its normal position on the relatively narrow edge of the sleeve 15 and to this end it is shown as resting on the top edge of the sleeve 15 and supported by the fuse element 10, preferably being provided with opposed notches 28 and 29 through which the fuse element passes, the fuse element being bent inwardly just beneath the element 25 sufficiently to normally support it in proper position. This partition element 25 defines a relatively small space within which that portion of the fuse element which vaporizes when the fuse blows is positioned and it thus limits the amount of oxygen available for combustion at the instant the fuse blows so that the amount of metal vaporized when this occurs is substantially reduced.

The pressure produced in this small chamber 26 when the fuse blows is sufficient to dislodge the disk 25 which is blown back into the chamber 27, as shown in dotted lines in Figure 1, so that the air within the chamber 27 is immediately available after the actual combustion ceases to cool the gaseous combustion products formed in the chamber 26, thus to reduce the pressure of gases within the fuse body. Moreover, these gases may vent from the body through the joint be-

tween the body, the base, and the external shell and the gases which thus escape are composed largely of the air normally within the chamber 27, this being relatively cool so that the gases 5 which are vented are of low temperature and cannot produce a fire risk. The upper portion of the body 5 surrounding the window 6 is of relatively thick material and is fully able to withstand the momentary action of the hot gases thereon 10 without danger of cracking, while the lower end of the body at the wall 4 is fully protected from the impingement of the hot gases thereon by the sleeve 15 and the disk 25. This disk 25 also tends to hold the fuse in position immediately in back 15 of the window and may be of a color to increase the visibility of the fuse element and thus be of material aid in detecting a blown fuse. It may also have printed thereon suitable marks indicating the capacity of the fuse readily visible 20 through the window 6.

From the foregoing description of an embodiment of this invention it should be evident to those skilled in the art that various changes and modifications may be made without departing 25 from its spirit or scope as defined by the appended claims.

I claim:

1. A fuse having a non-conductive base provided with a terminal, a transparent body portion 30 having a window opposite to said base, and a side wall extending theretoward, a threaded conductive shell enclosing said side wall, a fuse element having its opposite ends secured to said terminal and shell, respectively, and having an intermediate portion of reduced cross section back of said window, a protecting sleeve inwardly of and substantially against said side wall and between said wall and said fuse element, and a relatively 35 narrow edge, and a relatively flimsy sheet material member positioned back of

said intermediate fuse element portion and adjacent thereto and forming a partition normally dividing the space enclosed by said body and base into a pair of chambers in one of which said reduced cross sectional fuse portion lies, said sheet material member being supported on said edge free to give way under pressure produced when the fuse element blows, to unite said chambers. 80

2. A fuse having a non-conductive base provided with a terminal, a transparent body portion having a window opposite to said base and a side wall extending theretoward, a threaded conductive shell enclosing said side wall and having a portion engaging said base and holding said base and body portion assembled, a fuse element having its opposite ends secured to said terminal and shell, respectively, and having an intermediate portion of reduced cross section back of said window, a protecting sleeve within and substantially against said side wall and between said wall and said fuse element, and a sheet material member positioned back of said intermediate fuse element portion and adjacent thereto and to one end of said sleeve and forming a partition normally dividing the space enclosed by said body and base into a pair of non-communicating chambers in one of which said reduced cross section fuse portion lies and the other of which is vented to the atmosphere through the joint between said body portion base and shell. 95

3. A fuse comprising members defining a space, a partition normally dividing said space into two non-communicating compartments, means for venting one of said compartments, a fuse element having a blowing portion in the other of said compartments, and means for supporting said partition to give way under pressure produced when said fuse element blows. 100
